ODORLESS ALKYL ARYL SULFONATE
DETERGENTS

Richard D. Stayner, Berkeley, Calif., assignor to California Research Corporation, San Francisco, Calif., a corporation of Delaware

No Drawing. Application March 19, 1957
Serial No. 646,957

5 Claims. (Cl. 260—505)

The present invention relates to a process for producing substantially odorless alkyl aryl sulfonate detergents and to alkyl aryl hydrocarbon compositions which can be converted to these substantially odorless sulfonate detergents by known processing techniques of the art.

In the total volume of various synthetic detergents currently produced and sold on the market, the largest proportion consists of alkyl aryl sulfonate detergents such as are prepared by reacting an alkyl benzene containing from 9 to 18 carbon atoms in the alkyl group with concentrated sulfuric acid, and neutralizing the sulfonic acids thus produced. The alkyl benzene materials commonly employed for the preparation of these sulfonate detergents are polypropylene benzenes obtainable by alkylating benzene with a propylene polymer fraction containing from 9 to 18 carbon atoms in the polymer chain, and keryl benzenes produced by chlorinating kerosene and condensing the resulting alkyl chlorides with benzene.

It has been observed that upon completion of the sequence of sulfonation and neutralization steps in the manufacture of the aforementioned sulfonate detergents, particularly when branched-chain alkyl benzenes are employed for the sulfonation, the resulting neutralized sulfonate slurry has a rather unpleasant odor which resembles the characteristic odor of neutralized petroleum sludge produced in the sulfuric acid treatment of petroleum fractions. When alkyl aryl sulfonate detergents are blended with builders, in accordance with the conventional procedures of the art, to produce a final detergent composition containing from about 15 to about 40% of active detergent materials, the intensity of the odor is reduced; however, even after drying of the slurry to a solid particle-form material, the odor still remains high and persistent, and is difficult to mask by the conventional addition of perfume.

As a matter of fact, two types of odors have been observed in alkyl aryl sulfonate detergents: (1) the aforementioned odor, reminiscent of the neutralized acid sludge, which comes out from the detergent material immediately upon completion of the sulfonation and neutralization steps; and (2) a rancid odor which develops upon storage of sulfonate detergent formulations. This latter odor is more characteristic of the detergents derived from keryl benzene than of the polypropylene-derived detergents. When the keryl benzene sulfonate detergent compositions are stored at fairly high temperature, this marked disagreeable rancid odor invariably is developed. In the case of polypropylene benzene sulfonate detergents, this rancid odor is seldom observed and then only after prolonged storage at high temperature and in the presence of considerable amounts of moisture.

The prevention of the rancid odor in detergents during their storage is discussed in U. S. Patents Nos. 2,397,133, 2,469,376 and 2,469,378, all issued to Flett, who proposed to alleviate the drawback of rancid odor by introducing into the detergent composition: hydroxy-aromatic compounds, for instance, alpha-naphthol and thymol; amino-aromatic compounds, for instance, para-

2

benzyl amino-phenol; and heterocyclic organic compound, for instance, coumarin or dextrose. In contrast with these disclosures of the prior art which aimed at the elimination or at least a reduction of the rancid odor occurring upon storage, the present invention is concerned with the elimination of the neutralized acid sludge odor which characterizes a freshly prepared alkyl aryl sulfonate detergent. It has now been found that a substantially odorless alkyl aryl sulfonate detergent may be obtained by sulfonating a branched-chain alkyl benzene in the presence of from 0.02 to 0.1% of a quinone which may be either para-benzoquinone, or ortho-benzoquinone, or toluquinone (o-methyl-p-benzoquinone), or a mixture thereof, based on the weight of the alkyl benzene hydrocarbon material. Para-benzoquinone is particularly effective as an inhibitor of the neutralized acid sludge odor. The invention will be better understood from the following examples of the preparation of the detergent sulfonates without and with the quinone odor inhibitor.

20 *Example 1*

A polypropylene benzene hydrocarbon (200 g.) of the type described in the U. S. Patent No. 2,477,382 (issued to Lewis) and boiling in the range from about 500° F. to about 625° F., is sulfonated with 20% oleum. The acid is added to the hydrocarbon with constant stirring over a period of about one hour, a total of three mols of sulfuric acid being added for each mol of the hydrocarbon. After the addition of the acid is completed, the acid-hydrocarbon mixture is digested at a temperature of from about 85° to about 105° F. for about two hours, during which time the sulfonation reaction is completed. The resulting sulfonation product mixture is neutralized with sodium hydroxide. The resulting slurry has a strong odor characteristic of neutralized petroleum acid sludge. A portion of this slurry is drum-dried, but the dried particle-form likewise has a typical strong sludge odor.

40 *Example 2*

After repeating the sulfonation described in Example 1 and after the digestion of the sulfonation mixture, water is added thereto in an amount which reduces the concentration of the unreacted sulfuric acid to 80% by weight. 45 Upon settling for two hours at 140° F. an upper layer of predominantly alkyl benzene sulfonic acid and a lower layer of predominantly aqueous sulfuric acid are formed. The layers are separated, and the sulfonic acid layer is neutralized with sodium hydroxide. The resulting neutralized slurry again displays a strong odor characteristic of the neutralized acid sludge. When a portion of this slurry is drum-dried, it is observed that the sludge odor does not disappear.

55 *Example 3*

The process described in Example 1 is repeated. However, before the acid is added to the alkyl benzene, a small amount (0.1%) by weight of para-benzoquinone is dissolved in the alkyl benzene. The odor of the neutralized slurry is substantially less intense than the odor of the slurries produced in Examples 1 and 2. A similar reduction is observed in the case of solid particulate product recovered on drying the slurry.

65 The quinone odor inhibitor may be either added to the alkyl benzene before the sulfonation or very shortly thereafter, intimately mixing the alkyl benzene, the acid and the odor inhibitor, while the sulfonation reaction is under way. Adding the odor inhibitor to the alkyl benzene before the sulfonation is preferred. At least 0.01% by weight of the quinone should be added to achieve a sufficiently appreciable odor improvement. Additions of from 0.02 to 0.1% by weight, based on the alkyl benzene,

result in a practical absence of the neutralized acid sludge odor in both the neutralized slurries and the dried detergent particles, beads or flakes. Ortho-benzoquinone, toluquinone, and mixtures of ortho-benzoquinone, para-benzoquinone and toluquinone similarly effect a reduction of the neutralized acid sludge odor in the sulfonated and neutralized final slurry or in the dried particulate sulfonate product, provided these quinone additions are employed in a total amount of at least 0.01% by weight, and preferably from 0.02 to 0.1% by weight, based on the alkyl benzene hydrocarbon.

Although in the illustrative examples hereinabove, sodium hydroxide has been employed as the neutralizing agent for the sulfonation product, other metal hydroxides, such as ammonium hydroxide, potassium hydroxide, calcium hydroxide or magnesium hydroxide may be used for the neutralization without any adverse effect on the improvement of odor in the final product in accordance with the invention.

The reduction of the sludge odor due to the addition of the quinones achieved in accordance with the invention in the case of sulfonates derived from polypropylene benzene, is achieved in the case of fresh alkyl aryl sulfonate detergents produced from keryl benzenes.

It is to be noted that the action of para-benzoquinone, ortho-benzoquinone and toluquinone in reducing the odor level of freshly prepared alkyl aryl benzene sulfonates is specific. Other quinones, such as anthraquinone, duroquinone, naphthaquinone, and phenanthroquinone are ineffective. In fact, when Example 1 is repeated with either anthraquinone or duroquinone, the odor of the neutralized slurry is practically undistinguishable from the characteristic strong unpleasant odor of neutralized acid sludge, as observed for the slurry of the alkyl aryl benzene sulfonate in Example 1.

The manner in which para- and/or ortho-benzoquinone accomplish the elimination or at least a substantial reduction of the undesirable odor in the finished sulfonate detergent product is not understood. It is believed that the quinone additive must inhibit, during the sulfonation, the formation of the side-reaction products which impart the undesirable odor to the finished detergent product.

The use of benzoquinones and toluquinone in the manner described hereinabove is effective only to inhibit the development of the neutralized acid sludge odor in the freshly prepared detergent. Should the neutral sulfonate detergent product be stored at high temperature in the presence of an appreciable amount of moisture and for a prolonged period of time, a rancid odor quite different from the odor of the freshly prepared detergent is apt to develop, although usually this would not occur in actual practice in the case of alkyl aryl sulfonate detergents prepared from polypropylene benzene. However, to prevent the occurrence of this rancid odor in detergent sulfonates prepared from keryl benzene and left in storage, it is recommended that, after the sulfonation of the alkyl benzene containing the quinone inhibitor dispersed therein and after the neutralization of the resulting sulfonation product, a small amount of hydroquinone, usually

in an amount from 0.001 to 0.005% by weight, based on the alkyl benzene sulfonate, be added to the neutralized product slurry before drying it.

As pointed out hereinbefore, in order to effect the desired suppression of the neutralized sludge odor from the freshly prepared sulfonate detergent product the quinone should be added to the alkyl benzene either prior to the mixing of the hydrocarbon and the sulfuric acid, or very shortly after the mixing began. If added at a later time, for instance, towards the end of the sulfonation reaction or digestion, the addition is ineffective.

Solutions of para-benzoquinone, ortho-benzoquinone and toluquinone in C₉-C₁₈ alkyl benzenes constitute excellent raw materials from which one can produce alkyl aryl sulfonate detergents of good odor. Such solutions can be conveniently prepared by the manufacturer of the alkyl benzenes and shipped to the manufacturers of detergents, who may then directly sulfonate the solution, neutralize the resulting sulfonation product, add the necessary builders, and dry the built neutralized slurry.

I claim:

1. In a process for producing an alkyl aryl sulfonate detergent by sulfonating an alkyl benzene hydrocarbon having from 9 to 18 carbon atoms in its alkyl chain with concentrated sulfuric acid, neutralizing the sulfonation product and drying the neutralized product, the improvement which comprises dispersing from 0.02 to 0.1%, based on the weight of the alkyl benzene, of at least one quinone selected from the group consisting of para-benzoquinone, ortho-benzoquinone and toluquinone in the alkyl benzene hydrocarbon before the sulfonation reaction is complete.

2. A process for producing an alkyl aryl sulfonate detergent by sulfonating an alkyl benzene hydrocarbon having from 9 to 18 carbon atoms in its alkyl chain with concentrated sulfuric acid in the presence of 0.02 to 0.1% of at least one quinone selected from the group consisting of para-benzoquinone, ortho-benzoquinone and toluquinone, based on the weight of the alkyl benzene, neutralizing the sulfonation product, and drying the neutralized product.

3. A composition suitable for sulfonation and neutralization to produce a neutral sulfonation product free of neutralized acid sludge odor, comprising an alkyl benzene hydrocarbon having 9 to 18 carbon atoms in the alkyl chain, in which is dispersed from 0.02 to 0.1% by weight of at least one quinone from the group consisting of para-benzoquinone, ortho-benzoquinone and toluquinone.

4. A composition suitable for sulfonation and neutralization to produce a neutral sulfonation product essentially free of neutralized acid sludge odor, comprising an alkyl benzene hydrocarbon having 9 to 18 carbon atoms in the alkyl chain, in which is dispersed from 0.02 to 0.1% by weight of para-benzoquinone.

5. A composition as defined in claim 4, wherein said alkyl benzene hydrocarbon is polypropylene benzene.
